UNITED STATES PATENT OFFICE.

HARRY W. LOWE, OF INDIANAPOLIS, INDIANA; MARK W. LOWE, ADMINISTRATOR OF SAID HARRY W. LOWE, DECEASED, ASSIGNOR TO JOHN P. DALZELL, OF MINNEAPOLIS, MINNESOTA.

PULP-HEATING COIL.

Application filed March 26, 1919. Serial No. 235,142.

In cooking tomato pulp in tomato-canning plants, by the use of steam-carrying coils, it is desirable that the coils be maintained full of live steam without backing up, and that water be prevented from collecting in such coils, as the collection of water not only lengthens the time required for the cooking, but also produces a burning or scorching and a loss of color of the tomato pulp.

It is the object of my present invention to provide a coil construction which prevents the collection of water therein, and which allows the steam to pass through the coil without any backing up as on account of inequality in cooling in parallel-connected pipes extending through different parts of the pulp being cooked. By doing this, I greatly reduce the time required for cooking, avoid scorching, and maintain the natural tomato color.

The accompanying drawing illustrates my invention in its preferred form: Fig. 1 is a perspective view of a three-layer coil embodying my invention; Fig. 2 is a horizontal section through a pulp-container equipped with a two-layer coil embodying my invention, also showing part of the steam connections; Fig. 3 is a fragmentary vertical section through the container of Fig. 2, showing the steam connections more fully; Fig. 4 is a fragmentary horizontal sectional view through a segment of one of the coils at the intake; and Fig. 5 is a fragmentary horizontal sectional view through a segment of one of the coils at the outlet.

The coil may consist of a plurality of any number of superposed coil layers, three layers being shown in Fig. 1 and two in Figs. 2 and 3. The coil is mounted in a pulp-container 10, of any suitable type, conveniently provided with a discharge outlet 11 at the bottom for drawing off the cooked pulp. Each layer of the coil consists of one or more circles of pipe, though it is not essential that they be circular in form, and as shown comprises an outer pipe circle 12 and an inner pipe circle 13. At its receiving point, the left in Figs. 2 and 3 and the right in Fig. 1, each pipe layer is connected to a steam supply pipe 14, which, in the arrangement shown, leads by way of a fitting 15 to both pipe circles 12 and 13 and to the two portions of each pipe circle branch-

ing from such fitting; so that with the two-circle layer shown the steam divides at the fitting 15 into four streams, as shown in Fig. 4. At the discharge point, preferably opposite the receiving point, as shown, there is a fitting 16, which is divided into two parts by a central web 17. Into that part of the fitting on each side of such web one half turn of each pipe circle discharges, as is clear from Fig. 5. The web 17 thus prevents the interconnection of the discharge ends of the pipes on its opposite sides, so that in the arrangement shown it prevents a backing up of the steam in either half circle in case there exists any difference in pressure at the discharge ends of said two half circles as on account of differences in cooling action of the portions of the pulp through which such half circles pass. The portion of the fitting 16 on each side of the web 17 is connected by a separate L portion 18 to a separate discharge pipe 19. In the arrangement shown, the two discharge pipes 19 and the intake pipe 14 of each layer pass through the wall of the container 10 at substantially opposite points, and serve as supports for such layer. Outside the container 10, each discharge pipe 19 is connected to a separate downwardly extending pipe 20, which extends downward for a considerable distance and is then connected through a check valve 21 to a header 22 which is common to all the pipes 20. The height of each pipe 20 is sufficient so as to make certain that the head of water which may collect therein behind the check valve 21 will be sufficient to operate such check valve before the water backs up into the pipe 19 and the coil connected thereto. This ensures keeping the coils clear of water. The check valves 21 also prevent water from flowing backward through the pipes 20 into any one coil section in case anything happens to other coil sections or the discharge therefrom.

The header 22 connects by a pipe 25 to a receiving tank 26, for holding the condensed water discharged from the coil through the several pipes 19-20. From this tank 26 the collected water may be drawn at will, and, if desired, discharged by the steam pressure above it to any desired point, the discharge of water from the tank 26 being controlled in any suitable manner, as by a suit-

able valve 27. The tank 26 is provided with a water gage 28, connected to the tank at top and bottom, for indicating the water level therein, so that the operator may know the water level in the tank and may make sure that the amount of water does not become sufficient to back up the water into the coils. In order to guard against negligence on the part of the operator, I provide a float switch 29 operated by a float 30 responsive to the water level in the tank 26 for closing an alarm circuit, as of a bell 31 supplied from a battery 32, in case the water level in the tank 26 rises beyond a predetermined level.

The several coil layers are supplied with steam from a steam main 35, through a main valve 36 which controls the steam to all the coil layers. The steam for the lowermost coil layer passes direct from this valve 36 to the inlet pipe 14 of such coil layer, but the steam for the higher coil layer or layers passes through another valve 37 connected to a T 38 in the connection between the valve 36 and the lowermost coil layer. This is carried out for the succeeding coil layers in the same way, so that each controlling valve controls the supply of steam for its own coil layer and all the coil layers above it, and is connected through a T such as the T 38 to the supply pipe for the next lower coil layer between that coil layer and its controlling valve. By this arrangement, any upper layer or layers may be shut off by the operation of a single valve, leaving the coil layers below in operation, and the whole may be shut off by the operation of the main valve 36; but withal there are only as many controlling valves as there are coil layers. This arrangement is of considerable advantage, especially when but a small portion of pulp is being cooked, or when by the cooking the pulp has decreased in volume so as to uncover one or more coil layers.

45 I claim as my invention:

1. A pulp-cooking coil, comprising a plurality of pipe sections, for immersion in the pulp, a plurality of separate discharge connections for such pipe sections, a separate downwardly extending pipe from each dis-

charge connection, and a check valve connected to each downwardly extending pipe.

2. A pulp-cooking coil, comprising an intake fitting having a chamber, a plurality of pipe sections extending from such fitting and supplied from such chamber, a discharge fitting provided with a plurality of separated chambers and having such chambers connected to the discharge ends of different pipe sections, a separate downwardly extending discharge pipe from each chamber of said discharge fitting, and a check valve in each discharge pipe at a point sufficiently below the level of said pipe circles so that the head of water behind it will be sufficient to operate it before the water rises to the level of said coil.

3. A pulp-heating coil, comprising one or more pipe circles, an intake fitting connected to said pipe circles at one point so as to divide each pipe circle into two branching portions and having a chamber which supplies both portions of all such pipe circles in common, a discharge fitting connected to said pipe circles at another point and provided with two separated chambers each of which is connected to receive the discharge from one portion only of each pipe circle, a separate discharge pipe connected to each chamber of said discharge fitting, and a check valve in each discharge pipe at a point sufficiently below the level of said pipe circles so that the head of water behind it will be sufficient to operate it before the water rises to the level of said coil.

4. A pulp-cooking coil, comprising a series of pipe layers, a controlling valve connected to each pipe layer to control the flow therethrough, the valve for each higher pipe layer being connected on one side to its associated pipe layer and on the other side to the connection between the next lower pipe layer and its controlling valve.

In witness whereof, I have hereunto set my hand at 59 N. Irvington Ave., Indianapolis, Indiana, this 22nd day of March, A. D. one thousand nine hundred and nineteen.

HARRY W. LOWE.
